CLAIM

The ornamental design for a golf ball alignment tool, as shown and described.

DESCRIPTION

FIG. 1 is a top plan view of a golf ball alignment tool, the bottom plan view forming a mirror image thereof.

FIG. 2 is a left side elevational view of the golf ball alignment tool, the right side elevational view forming a mirror image thereof; and,

FIG. 3 is a front elevational view of the golf ball alignment tool, the rear elevational view forming a mirror image thereof.
